UNITED STATES PATENT OFFICE.

HOWARD M. DUDLEY, OF PHILADELPHIA, PENNSYLVANIA.

DYEING-MACHINE.

1,258,543.

Specification of Letters Patent. Patented Mar. 5, 1918.

Application filed December 22, 1916. Serial No. 138,310.

To all whom it may concern:

Be it known that I, HOWARD M. DUDLEY, a citizen of the United States, and a resident of Philadelphia, in the county of Philadelphia and State of Pennsylvania, have invented certain new and useful Improvements in Dyeing-Machines, of which the following is a specification.

My invention relates to a dyeing machine and refers particularly to a machine adapted for the dyeing of textile fibers compressed within a dyeing chamber, the dyeing being accomplished by the forced passage of the dye liquor through the fiber mass.

Among the objects of my invention is a dyeing machine particularly suitable for the dyeing of warps in the ball, whereby the condition of the fiber may be accurately and readily judged at any stage of the treatment without opening the dyeing chamber and whereby even results may be obtained without disturbing the fiber to be dyed.

Other objects of my invention will be evident upon a consideration of my specification and claims.

I have found that the even or uneven dyeing results obtained in a machine of this general character depends largely upon the particular shape of the openings through which the dye liquor enters the fiber mass, and that unevenness can be prevented by the use of openings of a particular shape, the conformation of which enables the liquor to spread itself through the fiber mass without the formation of channels of flow.

I have further found that this desirable result can be obtained if such openings are of a pyramidal form, diverging upwardly into the dyeing chamber or of a double diverging conformation, diverging both upwardly into the dyeing chamber and downwardly into the source of dye liquor, and further, that the evenness of the dyeing may be further enhanced by causing the dye liquor to pass through a chamber containing pyramidal shaped tubes before passing into the dyeing chamber.

Related forms of my device are shown in the accompanying drawings, in which similar parts are designated by similar numerals.

Figure 1 is a side view of one form of my

invention, partly broken away to disclose a portion in cross-section.

Fig. 2 is a cross-section through the line 2—2 of Fig. 1.

Fig. 3 is an enlarged cross-section of the pyramidal tubes introduced into the liquor supply chamber.

Fig. 4 is a top plan view of the pyramidal tubes.

Fig. 5 is a broken side view of one modification of my device showing an upper and lower arrangement of the pyramidal tubes in the liquor supply chamber.

Fig. 6 is a cross-section of the pump chamber showing the pyramidal tubes extending downwardly therein.

The outer portion of the dyeing machine comprises the rectangular shell 7 and the rectangular shell 8, fixedly attached to each other by the bolts 9, 9; the pyramidal shaped shell 10 fixedly attached to the shell 8 by the bolts 11, 11 and the centrifugal pump 12 fixedly attached to the shell 10 by the bolts 13, 13. A foraminous plate 14 is situated between the shells 7 and 8 integral with the walls of the shell 8. The foraminous plate 14 carries pyramidal shaped openings 16, 16 diverging both upwardly and downwardly from their centers.

The machine is provided with a removable annular foraminous plate 17, the construction of which is similar to the foraminous plate 14.

An annular angle-shaped member 18, is slidable within the shell 7, capable of abutment upon the plate 17 and maintained in any desired position by means of the thumbscrews 19, 19, which thread within the shoulders 20, 20 fixedly attached to the shell 7.

A series of pyramidal tubes 21, 21 are positioned in the interior portion of the shell 10, extending from the top to the bottom thereof, their upper ends 41, 41 and lower ends 42, 42 being flared or diverged.

In the modification shown in Fig. 5, the pyramidal tubes 21, 21 are replaced by pyramidal tubes 22, 22 extending downwardly from the top of the chamber within the shell 10, and pyramidal tubes 23, 23 extending upwardly from the bottom of the chamber within the shell 10, the two series of pyramidal tubes being in alinement with each other.

In the modification shown in Fig. 6 the

5 pyramidal tubes 23, 23 are replaced by pyramidal tubes 24, 24 which extend downwardly beyond the lower portion of the chamber within the shell 10 into the chamber of the rotary pump 12.

A perforated steam pipe 25 is introduced into the chamber formed by the shell 8.

10 In order to facilitate reference to the various chambers, they will hereafter be referred to as the top chamber 26, the dyeing chamber 27, the liquor supply chamber 28, the tube chamber 29, and the pump chamber 30.

15 An over-flow pipe 31 connects the top chamber 26 with the centrifugal pump 12 to allow of continuous flow of the liquor upwardly through the machine.

20 A pipe 32 connects the pump 12, with a liquor supply tank, not shown, the pipe 32 carrying the valve 33.

25 A pipe 34, 35 extends from within the liquor supply chamber 28 to a point above the top chamber 26, and carries a thermometer 36 for registering the temperature passing through the pipe 34, 35.

30 A sample dyeing machine 37, exactly similar to the above described dyeing machine, except in smaller proportions, is connected to the liquor supply chamber 28 by the pipe 38 and to the top chamber 26 by the pipe 39. The sample material in the machine 37 is examined by removing the top 40 which is threaded to the sample machine 37.

The operation of the device is as follows:

35 The annular member 18 and the foraminous plate 17 are removed, the goods to be treated introduced into the dyeing chamber 27, the plate 17 replaced and pressed down upon the goods by means of the member 18.

40 A small quantity of the same goods is placed in the sample device 37. The pump 12 is started and the valve 33 opened, allowing the liquor to flow through the pipe 32 into the pump 12, by which it is forced upwardly through the pump chamber 30, the tube chamber 29, the liquor supply chamber 28, and the goods in the dyeing chamber 27, into the top member 26. When the liquor has reached a height to allow its flow 45 through the pipe 31 back into the pump 12, the valve 33 is closed and the liquor is forced continuously through the device as above stated.

50 From time to time, the valve 51 is closed, the top 40 is removed for the purpose of examining the condition of the dyeing operation, and is then replaced, the valve 51 opened and the dyeing continued until it has reached a satisfactory condition.

55 It is evident that during this operation the liquor is forced upwardly through the pyramidal tubes 21, 21, the upper ends of which cause it to spread out upon leaving the tubes, the flow of the liquor thus exerting an upwardly divergent force. As the liquor leaves

the spaces in the foraminous plate 16, the divergent edges of the separating members cause it to spread out and to impinge upon the material in the dyeing chamber 27 in a practically uniform manner, and that the continuing of this flow will force the liquor throughout the mass of goods, and will prevent the formation of channels through the goods. As the plate 17 is the same as plate 16, the pressure will be maintained in the dyeing chamber 27, and the liquor will be compelled to penetrate the goods inwardly toward each of the openings in order to escape.

60 I do not limit myself to the size, shape, number or arrangement of parts as shown and described, all of which may be varied without going beyond the scope of my invention as described and claimed.

What is claimed, is:

65 1. In a dyeing machine, in combination, a receptacle, a foraminous plate having pyramidal upwardly divergent openings within the receptacle, a fiber chamber adjacent to the plate, means for compressing fiber within the chamber and upon the plate and means for forcing a liquid through the openings in the foraminous plate into the fiber chamber.

70 2. In a dyeing machine, in combination, a receptacle, a foraminous plate having pyramidal upwardly divergent openings within the receptacle and fixedly attached thereto, a second foraminous plate within the receptacle, means for maintaining the second plate at varying distances from the first plate, a fiber 75 chamber between the plates and means for forcing a liquid through the openings in the first plate, the chamber and the openings of the second plate.

75 3. In a dyeing machine, in combination, a receptacle, a foraminous plate having pyramidal upwardly divergent openings within the receptacle, a second foraminous plate within the receptacle, means for maintaining the two plates in any position of separation with respect to each other, a fiber chamber between the two plates and the sides of the receptacle and means for forcing a liquid 80 through the openings in the first plate, the chamber and the openings in the second plate.

85 4. In a dyeing machine, in combination, a receptacle, a foraminous plate having pyramidal upwardly divergent openings within the receptacle and fixedly attached thereto, a second foraminous plate having pyramidal downwardly divergent openings within the receptacle and above the first plate, means for moving the plates with respect to each other, and for maintaining the plates in a predetermined position, a liquid supply chamber below the first plate, a downwardly converging tube-carrying chamber, a series of tubes within the tube-carrying chamber, the ends of said tubes being divergent, 90

means for heating a liquid within the receptacle and means for forcing a liquid through the receptacle.

5. In a dyeing machine, in combination, a receptacle, two foraminous plates having pyramidal divergent openings within the receptacle, a fiber chamber between the two plates, means for compressing fiber within the chamber and between the plates and means for forcing a liquid through the openings of the one plate, the fiber chamber and the openings in the other plate.

6. In a dyeing machine, in combination, a receptacle, a foraminous plate having pyramidal upwardly divergent openings within the receptacle and fixedly attached thereto, a second foraminous plate having pyramidal downwardly divergent openings within the receptacle and above the first plate, means for moving the plates with respect to each other, and for maintaining the plates in a predetermined position, a liquid supply chamber below the first plate, a tube-containing chamber below the supply chamber, a series of pyramidal tubes within the tube-containing chamber, and means for forcing a liquid through the receptacle.

7. In a dyeing machine, in combination, a receptacle, a foraminous plate having pyramidal upwardly divergent openings within the receptacle and fixedly attached thereto, a second foraminous plate having pyramidal downwardly divergent openings within the receptacle and above the first plate, means for moving the plates with respect to each other, and for maintaining the plates in a predetermined position, a liquid supply chamber below the first plate, a downwardly converging tube-carrying chamber, a series of pyramidal tubes within the tube-carrying

chamber, the ends of said tubes being divergent, means for heating a liquid within the receptacle and means for forcing a liquid through the receptacle.

8. In a dyeing machine, in combination, a receptacle, a foraminous plate having pyramidal upwardly divergent openings within the receptacle and fixedly attached thereto, a second foraminous plate within the receptacle, means for maintaining the second plate at varying distances from the first plate, a fiber chamber between the two plates, a smaller testing device, similar and proportionate to and exterior to, the larger device, means for connecting the spaces below the foraminous plates to allow of the flow of a liquid and means for passing a liquid through the two devices.

9. In a dyeing machine, in combination, a receptacle, a foraminous plate having pyramidal upwardly divergent openings within the receptacle and fixedly attached thereto, a second foraminous plate having pyramidal downwardly divergent openings within the receptacle and above the first plate, means for moving the plates in a predetermined position, a liquid supply chamber below the first plate, a tube-containing chamber below the supply chamber, a series of pyramidal tubes within the tube-chamber, a smaller testing device, similar and proportionate to and exterior to, the larger device, means for connecting the spaces below the foraminous plates to allow of the flow of a liquid and means for passing a liquid through the two devices.

Signed at New York, in the county of New York and State of New York this 14th day of December 1916.

HOWARD M. DUDLEY.
